PANTS PROTECTIVE COVERING

Leonard Gladstone, New York, N. Y.

Application April 16, 1957, Serial No. 653,177

4 Claims. (Cl. 223—98)

This invention concerns an improvement in protectors for pants, trousers, slacks or the like.

Garments of the type described are usually folded midway and supported on a hanger having a transversely disposed bar or rod. In such garment supports the garment often becomes creased and wrinkled along the line where it is suspended at the hanger bar. In addition, the garment becomes soiled and discolored as dust and dirt accumulate and light falls upon the garment, particularly at the midsection which lies on the hanger bar. When these types of garments are on display in stores and retail establishments they are frequently handled by customers so that they become soiled and shopworn.

The present invention is directed at overcoming or minimizing the above difficulties and in addition to providing a means for protecting the garments, the invention serves to retain the garments on the hangers more securely. The invention also provides means for carrying price, style and information pertinent to the garment as well as means for carrying an advertising message.

According to the invention a transparent plastic tubing or sleeve is provided. The tubing is shaped to conform to the general shape of trousers or slacks. Suitable clips are provided to retain the tubing on the garment and to retain the garment on the hanger.

It is therefore a principal object of the invention to provide a garment protector in the form of a band, sleeve or tubing of transparent material.

It is a further object to provide a protector of the character described with clip means for retaining the device on a trousered garment and for retaining the garment on a hanger bar.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an elevational view of a garment protector embodying the invention, with the device tilted forwardly to show its structure more clearly.

Fig. 2 is an elevational view of the band mounted on a garment and carried on a hanger.

Fig. 3 is a longitudinal sectional view taken on lines 3—3 of Fig. 2 and showing details of construction on a large scale.

Fig. 3A is a view similar to Fig. 3 on a further enlarged scale showing another form of the invention.

Figs. 4 and 5 are elevational views of still further forms of the invention.

Fig. 5A is an elevational view of the band shown in Fig. 5 with the band folded along its midline.

Fig. 5B is a sectional view taken on lines 5B—5B of Fig. 5A.

Fig. 5C is a view similar to Fig. 5A showing a modified form of surface treatment.

2

Fig. 6 is a longitudinal sectional view taken on lines 6—6 of Fig. 5.

Figs. 7 and 8 are cross-sectional views taken on lines 7—7 and 8—8, respectively, of Fig. 5.

5 Fig. 9 is an elevational view of a garment with a garment protector according to the invention of Figs. 7 and 8 supported thereon.

Fig. 10 is a sectional view taken on lines 10—10 of Fig. 9.

10 The protector basically has the form shown in Fig. 1. An endless band 20 of tubing is provided. The band has a tapered form with a wider end 21 and a narrower end 22. The band is made of transparent plastic material such as polyethylene, a vinyl polymer, cellulose acetate, etc. The film of which the band 20 is made should be tough and have a suitably heavy gauge or thickness to withstand considerable handling and wear. Preferably, the material should be thermoplastic so that if it is made from flat sheets it may be heat-sealed by conventional 15 high frequency dielectric heating or other heat-sealing techniques.

The tapered form of the band 20 is intended to conform the band to the generally tapered shape of trousers, pants, or slacks P, such as shown in Fig. 2. In Fig. 2, band 20 is shown disposed at the midsection of a garment P and is folded over the bar 24 of a hanger 25 at the midline L of the band 20. The band is so shaped that the garment is snugly and smoothly retained within the band 20, and is smoothly draped over bar 24 as shown 20 in Fig. 3.

In Fig. 4, the band 20 is shown provided with indicia 28 denoting the style, price, and size of the garment. Squares 27 are provided for marking the desired numerals or lettering on the band. If desired, these squares may be 35 roughened portions so that the band can be more readily marked by a suitable marking crayon, rubber stamp, etc. An advertising message such as indicia 29 may also be provided on the band so that when the band is disposed on a garment, the advertisement will be in the view of 40 the customer.

In Figs. 3A, 5—8 the band 20 is shown provided with a pair of clips 30 at or near its wider end 21. These clips are U-shaped members integrally joined by a line 35 heat-sealed or the like at the bight 34 of the clip as shown 45 in Fig. 7. The arms 31 of each clip are not attached to the outer wall of the band, so that when the band is folded along its midline L as shown in Fig. 5A, the lower or narrower portion of the band is engaged under one arm 31 of each clip. The clips 30 are formed of thermoplastic

50 material of the same or different material as that of the band 20. The clips should be formed of considerably heavier gauge or thicker material than that of the band 20. The arms of the clips should have some flexibility so that they can be inserted over the garment and they should have an inward spring bias as indicated by arrows 36 when the band is folded and the arms of the clip engage 55 the lower portion thereof.

The free ends of the clips are so spaced that when the band 20 is mounted on a pair of trousers or other garment P as shown in Figs. 9 and 10 the band will not slip off because the arms 31 are then inwardly biased sufficiently to grip the sides of the garment. When the garment P is mounted on a hanger 25, as shown in Fig. 3A, the arms 31 of each clip grip the sides of the garment depending from bar 24 and prevent the garment from slipping off the hanger bar. They also prevent the garment from slipping out of the band 20.

If desired, one side of the band 20 can be embossed as shown in Figs. 5A, 5B and 6, with rounded dimples, 60 projections or corrugations 37 to increase the frictional hold of the band on the hanger bar and also to increase the frictional hold of the band on the garment. These 70

corrugations may be arranged to project only outwardly as shown in Fig. 5B, or both inwardly and outwardly as shown at 37' in Fig. 5C. Of course the entire body of the band can be embossed but it is preferable that only one side S be embossed and the other side S' left clear and smooth so that an unobstructed view is had of the texture and condition of the garment within the protective band.

When the band 20 is in use on a garment supported on a hanger, wrinkling and creasing at the midsection of the garment is prevented or reduced to a minimum extent. The garment can be taken off and replaced on the hanger without becoming soiled by the hands of the customer or salesman. When the garment is on the hanger and is being held for display or sale, dirt and dust which normally collects on the upper folded midsection of the garment falls on the protector instead where it can readily be removed. If desired, the plastic band may be formed of a tinted transparent material. The colored material may have a red tint and will serve to filter out ultraviolet rays present in daylight, as well as in incandescent and fluorescent light emitted by lighting fixtures. This use of the protector will prevent discoloration and fading of the garment caused by the ultraviolet rays.

The band is so constructed that it can easily be slipped off the garment so that a customer can try on the garment when desired. If the band with clips 30 is used, the flexible arms 31 can easily be separated with the fingers to release the band from the garment. The tapered shape of the band facilitates removal of the band as it is moved toward the narrow end of the garment.

While I have illustrated and described the preferred embodiments of my invention, it is to be understood that I do not limit myself to the precise constructions herein disclosed and that various changes and modifications may be made within the scope of the invention as defined in the appended claims.

Having thus described my invention, what I claim as new, and desire to secure by United States Letters Patent is:

1. A garment protector, comprising an endless band of transparent thermoplastic material, said band having a tapered shape, tapering in the direction of its length, and a pair of U-shaped clips disposed transversely on the band, said clips being formed of resilient thermoplastic material having a greater thickness than that of said band, each of the clips being secured near the wider end of the band by heat-sealing of the bights of the clips to the band so that the outer ends of the arms of the clips are free from the band, said ends being normally so spaced that when the band is disposed on the midsection of a trousered garment, the arms are biased inwardly to hold the band on the garment.

2. A garment protector, comprising an endless band of transparent thermoplastic material, said band having a tapered shape, tapering in the direction of its length, and a pair of U-shaped clips disposed transversely on the band, said clips being formed of resilient thermoplastic material having a greater thickness than that of said band, each of the clips being secured near the wider end of the band by heat-sealing of the bights of the clips to the band so that the outer ends of the arms of the clips are free from the band, said ends being normally so spaced that when the band is disposed on the midsection of a trousered garment, the arms are biased inwardly to hold the band on the garment, one side of the band having outwardly extending projections thereon to increase the frictional hold of the band on a garment hanger bar.

3. A garment protector, comprising an endless band of transparent thermoplastic material, said band having a tapered shape, tapering in the direction of its length, and a pair of U-shaped clips disposed transversely on the band, said clips being formed of resilient thermoplastic material having a greater thickness than that of said band, each of the clips being secured near the wider end of the band by heat-sealing of the bights of the clips to the band so that the outer ends of the arms of the clips are free from the band, said ends being normally so spaced that when the band is disposed on the midsection of a trousered garment, the arms are biased inwardly to hold the band on the garment and to hold the band and garment on a hanger bar, at least one side of the band having projections extending both inwardly and outwardly therefrom to increase the frictional hold of the band on the garment and the frictional hold of the band on the garment bar.

4. A trousered garment protector, comprising an endless band of transparent thermoplastic material, said band tapering in the direction of its length, said band having a pair of U-shaped clips disposed transversely on the band, said clips being formed of resilient thermoplastic material having a greater thickness than that of said band, each of the clips being secured near the wider end of the band by heat-sealing of the bights of the clips to the band so that the outer ends of the arms of the clips are free from the band, said ends being normally so spaced that when the band is disposed on the midsection of said trousered garment, the arms are biased inwardly to hold the band on the garment.
